UNITED STATES PATENT OFFICE.

WARREN W. ANNABLE, OF GRAND RAPIDS, MICHIGAN, ASSIGNOR TO C. VALLETTE KASSON,
OF CHICAGO, ILLINOIS.

TRACK-GRINDER.

No. 872,493.

Specification of Letters Patent.

Patented Dec. 3, 1907.

Application filed August 11, 1906. Serial No. 330,181.

To all whom it may concern:

Be it known that I, WARREN W. ANNABLE, a citizen of the United States, residing at Grand Rapids, in the county of Kent and 5 State of Michigan, have invented certain new and useful Improvements in Track-Grinders; and I do hereby declare the following to be a full, clear, and exact description of the invention, such as will enable others skilled 10 in the art to which it appertains to make and use the same.

My invention relates to track grinders, and more particularly to such grinders adapted to reducing inequalities at the joints of the 15 rails of car track, after the rails are in position, and its object is to provide a device which will rapidly and effectually perform this work; that may be handled by one operator, that is provided with means for self 20 propulsion from place to place as occasion for its use may require.

My device consists essentially of a truck upon which is mounted a motor to provide power for propulsion, and to drive the grinders, a clutch between the motor and the propelling gearing, a counter shaft, grinder heads driven from the counter shaft, a reversible feed mechanism adapted to traverse the machine to and fro longitudinally of the 25 rails, means to traverse the grinder heads to and fro transversely of the rails, means for raising and lowering the grinder heads, means for contacting the grinding wheels with the rails and adjusting said wheels laterally of the rails, and in the combination 30 and arrangement of the various parts as hereinafter more fully described and particularly pointed out in the claims, reference being had to the accompanying drawings, in 35 40 which:

Figure 1. is a side elevation with parts removed; Fig. 2. a plan view of the same with other parts removed; Fig. 3. a transverse vertical section, looking forward, taken on 45 the line 3—3 of Fig. 1.; and, Fig. 4. a detail of the feed mechanism shown in front elevation.

Like numbers refer to like parts in all of the figures.

1 represents a truck frame mounted on axles 2 and 3. Upon this frame is mounted a second frame 4 with elevated portions 5 to carry the trolley pole (not shown) to conduct the current to the controller 20 and to the 50 motor 6.

Fixed on the armature shaft 7, is a pulley 13, which through a belt 16 and pulley 15 on the counter shaft 14 serves to drive said counter shaft when the belt tightener 17 is down. This countershaft 14 is mounted in 60 elongated journal bearings 46, upon the outside of which journal bearings and adapted to slide longitudinally thereon, are mounted double yoke arms 22, on the vertically swinging ends of which are journaled arbors 23 65 carrying abrasive wheels 24, and having pulleys 52 to which motion is imparted by belts 48 engaging pulleys 47 fixed on the counter-shaft 14. Attached to the inner end of these yokes 22 are levers 45 by which the yokes are 70 slidably traversed on the bearings 46, thus traversing the abrasive wheels transversely across the rails to be ground.

To provide for vertical movement of the abrasive wheels 24, there are provided screws 75 27 journaled in the frame 4, and provided with hand wheels 28 at their upper ends. These screws engage a nut 25 having opposing extensions 25 slidable in ears 26 on the yoke arms 22. To take up any lost motion 80 in this adjusting means, a contractile spring 29 is attached to the frame 4 at its upper end and connected to the arms 22 at their lower ends.

The means for moving the machine from 85 place to place consists of a shaft 8 journaled in bearings on the frame work 4 and in line with the armature shaft 7. On the inner end of this shaft 8 is one member of a magnetic clutch 9, the other member of which is the 90 web of the pulley 13, which pulley is fast on the armature shaft 7. On this shaft 8 is a pinion 8^a, which meshes with an idler gear 10, journaled on the stationary shaft 10^a. Journaled on a stud 11^a is another idler 95 gear 11 which is in mesh with the idler gear 10 and a gear 12 fixed on the axle 2.

To obtain the longitudinal feed when grinding, the machine is traversed to and fro by means of a gear 30 fixed on the axle 100 3, and in mesh with the pinion 31 fixed on the shaft 56, which shaft is journaled in a frame 55. On the shaft 56 is also fixed a worm gear 32, which is engaged by a worm 33 fixed on the shaft 36, which shaft is 105 mounted in a pivoted frame 37.

Slidable on the shaft 36 is a splined hub 36^a, on which are fixed bevel gears 34 and 35 adapted to alternately mesh with a bevel pinion 54 fixed on the inner end of a shaft 110

51. On the opposite end of this shaft is a pulley 49 to which motion is transmitted from a pulley 53 on the countershaft 14 by means of a belt 50. This shaft 51 is journaled at the outer end on the frame 4 and at the inner end on the frame 55. To cause the bevel gears 34 and 35 to alternately mesh with the bevel pinion 54, a pivoted lever 44 is provided having a yoke at its inner end, which engages a groove in the splined hub 36^a, to shift the same longitudinally on the shaft 36 and thus reverse the motion of rotation of the same.

When moving the machine from place to place it is necessary to disengage the worm from the worm gear. For this purpose the frame 37 is pivoted at the rear on the frame rod 38 and detachably supported on the frame rod 39 at the front. To raise and lower the front of the frame, a lever 41 is pivoted on a standard 42 and connected by a link 40 to the front of the frame.

When the worm 33 and worm gear 32 are in mesh, the forward end of the frame 37 rests on the rod 39, the lever 41 engages a notch 43^a in a catch 43 and thus the gears are locked in mesh. When it is desired to disengage the worm and worm gear, the lever 41 is depressed and caused to engage the notch 43^b in the catch 43. This raises the front end of the frame 37 off from the rod 39, and high enough so that the worm 33 is clear of the worm gear 32.

The operation of my device is as follows: When moving from place to place the belt tightener 17 is raised so that the belt 16 is loose. The abrasive wheels 24 are raised to clear obstructions, the worm 33 is thrown out of mesh with the worm gear 32, the electric switch that operates the magnetic clutch 9 is thrown in. In this condition the machine is run over the road and operated from the controller 20 with the same facility as any motor car. When the machine has arrived at its place to work, the switch that operates the magnetic clutch is opened, the belt tightener is put on the belt 16, the worm and worm gear are put in mesh, the abrasive wheels lowered to operative position and the device is ready for grinding the rails, lateral adjustment by means of the levers being used for curves or to shift the contact of the rim of the wheels, as occasion requires. Thus I provide a machine which is rapid, efficient, and is handled entirely by one operator.

What I claim is:—

1. In a track grinder, the combination of a truck, abrasive wheels mounted on the truck and adapted to be brought in contact with the track rails, a motor mounted on the truck, and means for simultaneously connecting the motor with the abrasive wheels and one pair of the truck wheels, means for disconnecting the motor from the abrasive

wheels and said truck wheels, and means for connecting the motor to the other pair of truck wheels.

2. In a track grinder, the combination of a truck, a motor mounted on the truck, gears connecting the motor and one of the truck axles, a clutch between the gears and the motor, abrasive wheels carried by the truck and adapted to be brought in contact with the track rails, and means for simultaneously connecting or disconnecting the motor with the abrasive wheels and with the other truck axle.

3. In a track grinder, the combination of a truck, a motor mounted on the truck, means for connecting said motor to one of the axles of the truck, a clutch between the motor and said means, abrasive wheels carried by the truck and adapted to be brought in contact with the track rails, means for both vertically and transversely adjusting said abrasive wheels relative to the track rails, and means for simultaneously connecting or disconnecting the abrasive wheels with the motor and with the other truck axle.

4. In a track grinder, the combination of a truck, a motor mounted on the truck, means for connecting the motor to one axle of the truck, vertically swinging arms mounted on the truck, means for both vertically and horizontally adjusting said arms, abrasive wheels mounted on the swinging ends of the arms, and means for driving the abrasive wheels from the motor.

5. In a track grinder, the combination of a truck, abrasive wheels carried by the truck, a motor mounted on the truck, means for driving the abrasive wheels by the motor, means for connecting the motor to the axle of the truck, and means actuated by the motor for slowly moving the machine to and fro over the track when grinding, said means being detachably connected to the motor.

6. In a track grinder, the combination of a truck having two axles, a motor mounted on said truck and detachably connected to one of said axles, a countershaft detachably connected to said motor, swinging arms slidably journaled at one end on the countershaft, abrasive wheels journaled on the swinging ends of said arms, means for vertically adjusting said abrasive wheels, means for sliding said arms on the countershaft to horizontally adjust the abrasive wheels relative to the track rails, and means for slowly traversing the machine to and fro when grinding said means being detachably connected to the countershaft and to the other of said axles.

7. In a track grinder, the combination of a truck, a motor mounted on the truck, means for connecting the motor with the truck axle, a countershaft mounted on the truck, swinging arms journaled on the countershaft at one end, abrasive wheels carried on the

- swinging ends of the arms and driven from the countershaft, adjusting screws acting on the swinging ends of the arms, reversible propelling means to slowly traverse the machine to and fro over the track when grinding, said means being driven from the countershaft, and means for connecting or disconnecting the motor with the countershaft.
8. In a track grinder, the combination of a truck having two axles, a motor mounted on the truck and detachably connected to one of the axles, a countershaft journaled on the truck and detachably connected to the motor, swinging arms journaled on the counter- 5 shaft and slidably longitudinally thereon, abrasive wheels carried on arbors mounted on the swinging ends of said arms and driven from the countershaft, levers attached to said arms to impart a horizontal motion thereto, shafts journaled on the truck and provided with hand wheels at one end and provided at the other end with screw threads which connect with the swinging ends of the arms to vertically adjust the same, and 10 means for slowly traversing the machine to and fro over the track when grinding.
9. In a track grinder, the combination of a truck having two axles, a motor mounted on the truck, means for driving one of the axles from the motor, a countershaft, arms journaled on the countershaft at one end, arbors journaled in the other end of the arms, abrasive wheels mounted on said arbors, pulleys on the countershaft and on said arbors, belts 15 to drive the arbors, a pulley on the motor, a pulley on the countershaft, a slack belt connecting the countershaft pulley to the motor pulley and an adjustable tightener for said belt.
10. In a track grinder, the combination of a truck having two axles, a motor mounted on the truck, a countershaft journaled on the truck, swinging arms journaled on the countershaft at one end and having arbors 20 journaled in the other ends, abrasive wheels mounted on said arbors, means for driving said arbors from the countershaft, adjusting means connected to the swinging end of said arms to adjust the abrasive wheels relative 25 to the track rails, a shaft having a bevel pinion at one end and driven from the counter- 25 shaft, a second shaft, a splined hub slidable thereon, two bevel gears fixed on said hub and adapted to alternately engage said bevel pinion, a lever to move said hub to alternately engage said bevel gears and pinion, and means for detachably connecting said second shaft with one axle of the truck.
11. In a track grinder, the combination of a truck having two axles, a motor mounted on the truck and geared to one of said axles, a clutch between the gears and motor, a countershaft journaled on said truck, swinging arms journaled at one end on the countershaft, arbors carrying abrasive wheels 60 journaled on the opposite ends, means for driving the countershaft and abrasive wheels from the motor, a shaft driven from the countershaft and having a bevel pinion at its end, a second shaft, a hub splined and slid- 65 able thereon, a lever to slide said hub, two bevel gears fixed on said hub and adapted to alternately mesh with said bevel pinion, a worm on said second shaft, a worm gear fixed on a third shaft and adapted to mesh 70 with said worm, means for engaging or disengaging said worm and worm gear, and a gear train to connect said third shaft with the other of said truck axles, whereby the machine may be moved slowly to and fro 75 when grinding.
12. In a track grinder, the combination of a truck having two axles, a motor mounted on said truck, a gear train between said motor and one axle of the truck, a clutch 80 between the gear train and motor, a counter-shaft mounted on the truck and driven from the motor, swinging arms journaled on the countershaft and longitudinally slidable 85 thereon, arbors journaled on the swinging ends of the arms and driven from the countershaft and carrying abrasive wheels, hand levers for slidably adjusting said arms on the countershaft, screw threaded shafts journaled on the truck and connected to the swinging 90 ends of said arms to vertically adjust the abrasive wheels relative to the rails, a shaft having a bevel pinion on one end and driven from the countershaft, a second shaft having 95 a hub splined and slidable thereon, two bevel gears fixed on said hub and adapted to alternately mesh with said pinion by the 100 slide motion of said hub, a hand lever to slide said hub, a worm on said second shaft, a third shaft having a worm gear adapted to mesh with said worm, means for throwing said worm and worm gear in or out of mesh, and a gear train from said third shaft to the 105 other axle of the truck, whereby a reversible motion is transmitted thereto, to slowly traverse the machine to and fro over the track when grinding.

In testimony whereof I affix my signature in presence of two witnesses.

WARREN W. ANNABLE.
